CLAIM

I claim the ornamental design for a precipitate infusion filter, as shown and described.

DESCRIPTION

FIG. 1 is an exploded isometric section view of the precipitate infusion filter showing my unique design, taken at line 1-1 as shown in FIG. 3;

FIG. 2 is an orthographic front section view thereof taken at line 2-2 as shown in FIG. 3;

FIG. 3 is an orthographic top view thereof;

FIG. 4 is an orthographic front view thereof;

FIG. 5 is an orthographic bottom view thereof; and,

FIG. 6 is an orthographic right side view thereof.
